J. C. ANDEREGG

SLIDE FOR AUTOMATIC FASTENERS

Original Filed June 26, 1926

J. C. Anderegg

By Watson E. Coleman
Attorney

UNITED STATES PATENT OFFICE.

JOSEPH C. ANDEREGG, OF ALGOMA, WISCONSIN.

SLIDE FOR AUTOMATIC FASTENERS.

Application filed June 26, 1926, Serial No. 118,821. Renewed March 31, 1928.

This invention relates to a slide for an automatic fastener and it is an object of the invention to provide a device of this kind comprising wings having diverging portions for coaction with the members of the fastener, together with means for effectually holding the wings against spreading and also to effect a separation of the members of the fastener when the slide is moved with respect thereto in the desired direction.

The invention consists in the details of construction and in the combination and arrangement of the several parts of my improved slide for an automatic fastener whereby certain important advantages are attained and the device rendered simpler, less expensive and otherwise more convenient and advantageous for use, as will be hereinafter more fully set forth.

20 The novel features of my invention will hereinafter be definitely claimed.

In order that my invention may be the better understood, I will now proceed to describe the same with reference to the accompanying drawing, wherein:

25 Figure 1 is a fragmentary view in elevation illustrating a slide constructed in accordance with an embodiment of my invention and in applied position;

30 Figure 2 is a view in side elevation of the slide as herein disclosed unapplied;

Figure 3 is a view in top plan of the slide as herein set forth;

35 Figure 4 is a view in plan of the slide substantially in blank.

As disclosed in the accompanying drawing, 1 denotes the marginal portions of material bordering an opening or gap 2 and which portions carry interlocking fastening members M. These members M are preferably of a type particularly illustrated in my application for patent executed on even date herewith.

Coacting with the members M is a slide 45 S. The major portion of this slide is preferably formed of a single blank of sheet metal of requisite gauge and comprises the wings W having their opposed end portions tied or connected at their central part by 50 an integral web or plate 3. The web or plate 3 is of a length whereby the wings W when folded in overlying relation are spaced apart a distance to readily receive therebetween the members as the slide S is moved 55 along the opening or gap 2.

The inner or connected end portions of the wings W are provided with the diametrically opposed and substantially V-shaped lateral extensions 4 and the outer marginal portions of said extensions 4 are 60 defined by the inwardly disposed flanges 5 continued along the adjacent outer marginal portion of the wing W proper.

The outer portions of the wings W are of a width to closely approximate the inner 65 ends of the members M or those end portions attached to the fabric so that the flanges 5 as the slide S is moved in one direction will have requisite coaction with the members M to cause the same to have requisite inward relative swinging movement to effect the desired interlocking engagement therebetween.

The web or plate 3 at its transverse center is longitudinally slotted, as at 6, the extremities of the slot 6 being in communication with the openings 7 provided in the portions of the wings W immediately adjacent to the web or plate 3.

75 The slot 6 permits requisite separation of 80 the adjacent portions of the plate or web 3 to permit the requisite application of the intermediate portion 8 of a staple member A. After the staple A has been applied such portions of the web or plate 3 adjacent 85 to the slot 6 are returned to overlie said portion 8 of the staple and thus effectively maintain the same in applied position.

The intermediate portion 8 of the staple A extends beyond the outer faces of the overlying wings W whereby the side members or legs 9 of the staple A have close contact therewith and thus effectually holding the wings W against spreading. These side members or legs 9 are of a length to closely approach the outer or free ends of the wings W and are held against swinging movement by having their extremities received between the outstanding knobs or protuberances 10 carried by the wings and preferably pressed 100 outwardly therefrom.

Engaged with one of the side members or legs 9 is a tab 11 to facilitate the requisite manipulation of the slide S.

With the members M in interlocking engagement, the requisite movement of the slide S will bring the intermediate portion 8 of the staple A into contact with the inwardly inclined outer end faces 12 of the members M thereby effecting a separation 110

thereof as is believed to be clearly apparent to those skilled in the art to which the present invention appertains.

From the foregoing description it is thought to be obvious that a slide for an automatic fastener constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

20 A slide of the class described, comprising spaced wings, a web connecting similar ends of the wings and longitudinally slotted, the

opposed ends of the wings having openings therethrough communicating with the ends of the slot, a staple having its intermediate portion bridging the space between the wings and positioned inwardly of and closely adjacent to the web parallel with said slot, the side members of the staple extending from the openings outwardly of the wings and in close contact therewith, and means carried by the wings for holding the side members of the staple against swinging movement, the slot in the web permitting separation of adjacent portions of the web to permit application of the intermediate portion of the staple, said separated portions being returned to overlie said intermediate portion of the applied staple to maintain the staple in such position.

In testimony whereof I hereunto affix my signature.

JOSEPH C. ANDEREGG.
